MALCOLM HARD, OF FLUSHING, NEW YORK, ASSIGNOR TO THE SUPERHEATER COMPANY, OF NEW YORK, N. Y., A CORPORATION OF DELAWARE.

CONTROLLING DEVICE FOR EXHAUST-STEAM INJECTORS.

Application filed August 12, 1925. Serial No. 49,724.

This invention relates to steam injectors of the type which are designed for operation primarily by exhaust steam from an engine, the action of which steam is supplemented by a supply of live steam in order to secure the pressure required at the delivery nozzle of the injector to overcome the boiler pressure. It has been found in practice that under normal running conditions it is necessary to supply the injector with very little or almost a negligible amount of supplementary live steam and that it is only necessary to open the supplementary live steam line to its fullest extent when certain critical conditions exist. It has also been found that the impulse of the average engineman or operator is to throw the injector controls wide open, thus causing a greater amount of live steam to be used than is necessary. Consequently, an excess amount of live steam is used and the injector is therefore not operated under the most efficient or economical conditions.

It is the principal object of the present invention to provide a new and improved controlling device, for an injector of the type referred to, by means of which the operation of the injector under the most efficient and economical conditions will be secured.

The above and other objects of the invention will appear more fully from the following more detailed description and by reference to the accompanying drawings forming a part hereof, and wherein Fig. 1 is a side elevation of a controlling device for an exhaust steam injector, the injector being shown in section; Figs. 2, 3 and 4 are enlarged details of the controlling device, Fig. 2 being an enlarged side elevation, partly in section, Fig. 3 a section on the line 3-3 of Fig. 4 and Fig. 4 a section on the line 4-4 of Fig. 3.

For the purpose of illustration, the controlling device is shown in the drawings as connected with an injector 10, which, as shown, is provided with a main steam nozzle 11, a combining nozzle 12, a delivery nozzle 13 and a supplementary live steam nozzle 14. Exhaust steam is admitted to the injector through the exhaust steam inlet 16 which is provided with a valve 17, adapted to be held to its seat by the pressure of the exhaust steam and to be opened against such

pressure by the fluid pressure actuating means 18, operated in a manner to be herein-after described.

The controlling device herein disclosed consists of a valve casing 20, having an inlet 21 to which is connected the pipe 22 which leads to any suitable live steam supply, as for example, the steam turret of the engine boiler. Mounted in a suitably screw threaded stuffing box 23, secured to the casing 20, is a valve rod 24, adapted to be actuated by the manually operable control handle 25 secured to the outer end of said valve rod. The inner end of said rod is swivelly connected to the main valve 26 which consists of a pair of swivelly connected valve members 26^a and 26^b. The valve member 26^a controls the passage of steam from the entrance chamber 27 of the valve casing 20, to the laterally extending passage 28, which leads to the outlet 29, connected by the pipe 30 to the injector 10 for supplying live steam to the supplementary live steam nozzle 14. The inner end of the valve member 26^a is provided with guides 26^c arranged in the form of radially extending webs, between which, passages are formed for the live steam to pass to the valve member 26^b. The valve member 26^b controls the flow of the live steam from the passage 31 to a chamber 32 of the valve casing in which chamber is mounted an automatic valve 33. Upper and lower seats 33^a and 33^b are provided on the valve 33 and are adapted to engage respectively with the cooperating seats 34^a, 34^b, of the valve casing (see Fig. 4). Slidably mounted in a suitable bearing cap 35, immediately above the automatic valve 33, is a fluid pressure responsive member 36, which is shown as a valve shaped structure, but which may be of any suitable or well known construction. Connected to the valve casing 20 and in communication with the interior thereof, immediately above the member 36, is one end of a pipe 37, the other end of which leads to the main steam line or the exhaust steam line of the engine. Below the lower valve seat 34^b for the automatic valve 33, the chamber 32 communicates through a lateral passage 38, with the outlet 39, from which the pipe 40 leads to the injector to supply it with auxiliary live steam.

Located between the upper valve seat 34^a

and the fluid pressure member 36, is a widened channel 41, with which a pipe 42 communicates, said pipe leading to a chamber 43 of the injector and serving under certain conditions to be hereinafter described to conduct steam to the fluid pressure member 18 slidably mounted in said chamber. Encircling and secured to the radial guides 26^a of the valve member 26^a is a sleeve 45, see Fig. 3, which is adapted when the valve rod 24 is unscrewed to its fullest extent to move across and close the lateral passage 28 leading to the outlet 29 for the supplementary live steam.

15 The operation of the device is as follows; if it is desired to start the injector, the control handle 25 is manipulated to move the main valve members 26^a, 26^b to the left (Fig. 3), thus lifting the valve member 26^a off its seat and permitting the live steam from the entrance chamber 27 to flow through the passages between the radial guides towards the valve member 26^b. In the first movement of the valve rod the valve member 26^b will remain seated because of the lost motion (as clearly shown in Fig. 3), provided in the swivel connection between the members 26^a, 26^b. A portion of the steam passes through the lateral passage 28 to the outlet 29 and thence through the pipe 30 to the supplementary live steam nozzle 14 of the injector, thus providing a preliminary steam flow in the injector. As the valve rod 24 is unscrewed further, the valve member 26^b is unseated and a portion of the steam flows to the chamber 32, for the automatic valve. If there is steam under pressure in the pipe 37, exhaust steam will therefore be available for operating the injector, and the automatic valve will be held by the member 36 upon its lower seat 34^b. The steam entering chamber 32 will, under these conditions, pass upwardly to the widened annular channel 41 from which it will pass through the pipe 40 to the chamber 43 of the injector and raise the member 18. The upper end of the member 18 being forced upwardly by the steam will contact with the exhaust steam valve 17 and raising said valve off its seat will permit the exhaust steam to flow through the injector. If there is no steam under pressure in the pipe 37, the live steam entering chamber 32 will raise the automatic valve off its seat 34^b and such steam will pass downwardly (Fig. 4) through the lateral passage 38 to the outlet 39 and thence through the pipe 40 to the injector.

60 It will be seen that when the controlling device is provided with the sleeve 45, should the engineman follow the natural impulse to throw the injector wide open, he will unconsciously have turned the valve to its most economical setting, or if he has thrown the valve handle too far so that the steam is entirely shut off from the supplementary nozzle,

the injector will spill through the overflow and he will necessarily have to adjust the handle to its correct position.

It will be understood that the present disclosure is merely illustrative of a satisfactory valve casing or main controlling device equipped with my invention, and that obviously many changes, variations and modifications of the control might be resorted to without departing from the spirit of my invention.

I claim:—

1. The combination with an exhaust steam injector adapted primarily for operation by exhaust steam and having a conduit connected therewith for supplying live steam to supplement the action of said exhaust steam, of a valve for controlling the admission of said live steam to said injector, and means secured to said valve to throttle the supply of live steam when said valve is moved substantially to its full opened position.

2. The combination with an exhaust steam injector adapted primarily for operation by exhaust steam and having a conduit connected therewith for supplying live steam to supplement the action of said exhaust steam, of a valve for controlling the admission of said live steam to said injector, said valve being provided with a manually operable handle and means secured to said valve to throttle the supply of live steam when said handle is thrown to a position corresponding substantially to the full opening of said valve.

3. The combination with an exhaust steam injector adapted primarily for operation by exhaust steam and having a conduit connected therewith for supplying live steam to supplement the action of said exhaust steam, of a valve for controlling the admission of said live steam to said injector, and a sleeve secured to said valve, said sleeve being constructed and arranged to throttle the admission of steam to said conduit when said valve is moved substantially to its full opened position.

4. The combination with a controlling device for an exhaust steam injector in which a manually operable main control valve is provided for controlling the admission of exhaust steam and supplementary live steam to said injector, of means connected with said valve for throttling the supply of live steam to said injector when said valve is moved substantially to its full opened position.

5. The combination with an exhaust steam injector adapted primarily for operation by exhaust steam and having a conduit connected therewith for supplying live steam to supplement the action of said exhaust steam, and a valve for controlling the admission of said live steam to said injector,

said valve being provided with a manually operable handle movable between two extreme positions, in one of which said valve is closed and in the other of which it is 5 fully open, of means connected with said valve to throttle the supply of live steam to said injector to the proper amount for normal operating conditions of the injector when said handle is moved adjacent to the 10 said other position.

6. The combination with an exhaust steam injector adapted primarily for operation by exhaust steam and having a conduit connected therewith for supplying live steam 15 to supplement the action of said exhaust steam, and a valve for controlling the admission of said live steam to said injector, said valve being provided with a manually operable handle movable between two extreme 20 positions, in one of which said valve is closed and in the other of which it is fully open, of an auxiliary valve associated with said first named valve to throttle the supply of live steam to said injector to the 25 proper amount for normal operating conditions of the injector when said handle is moved to the said other position, said auxiliary valve permitting the full supply of

live steam to pass to said injector when said manually operable handle is situated between said two extreme positions. 30

7. The combination with an exhaust steam injector adapted primarily for operation by exhaust steam and having a conduit connected therewith for supplying live steam to supplement the action of said exhaust steam, and a valve for controlling the admission of said live steam to said injector, said valve being provided with a manually operable handle movable between two extreme 35 positions, in one of which said valve is closed and in the other of which it is fully open, of a sleeve associated with said first named valve and movable therewith to a position in which the supply of live steam to said injector is throttled to the proper amount for normal operating conditions of the injector when said manually operable handle is moved to the said other position, and said sleeve being located in a position 40 in which said supply of live steam will not be throttled when said handle is located between said two extreme positions. 45

In testimony whereof I have signed this specification.

MALCOLM HARD.
